CENTRALIZED TRAFFIC CONTROLLING
SYSTEM FOR RAILROADS

Neil D. Preston, Rochester, N. Y., assignor to General Railway Signal Company, Rochester, N. Y.

Original application May 16, 1936, Serial No. 80,095, now Patent No. 2,169,480, dated August 15, 1939. Divided and this application December 15, 1937, Serial No. 179,982

10 Claims. (Cl. 177—353)

This invention relates to centralized traffic controlling systems for railroads and it pertains more particularly to the communication part of such systems, and is a division of my prior application Ser. No. 80,095, filed May 16, 1936, which has now matured into Patent No. 2,169,480 dated August 15, 1939.

In railroad traffic controlling systems the traffic is controlled from a control office usually located at a central point with respect to an outlying field station or a plurality of field stations. The field station or stations are connected to the control office by means of the communication system. The location of trains and the condition of the various traffic controlling devices at the outlying field station or stations are indicated to the attendant in the control office. These indications relating to the condition of the traffic controlling devices and the like are transmitted to the control office by means of the communication system.

The present invention is particularly useful in a system which is called upon to carry out a relatively large number of controls and indications during a short time. The present embodiment more particularly relates to a system comprising a control office and a single station although it will be understood that the invention is not limited to a single station.

The communication system provided interconnects the control office and the field station and it is so organized that complete control and supervision of the various devices, such as the track switch and the signals therefor, are obtained by the operator. Such a traffic controlling system is supplemented by the usual automatic block signal system and other local means ordinarily provided to guard against unsafe train movements, improper operation of track switches and the like.

In accordance with the preferred form of the present invention and illustrated in Figs. 1, 2 and 3, the communication system comprises a three wire line circuit extending from the control office to the outlying field station. The three line wires are referred to in this disclosure as the A line, the C line and the B line. The A line and the C line in combination are used for the transmission of controls. The B line and the C line in combination are used to effect the synchronous stepping of the step-by-step mechanisms in the control office and at the field station. The B line and the C line in common are also used to transmit indications from the station to the control office. Thus the C line is a

common return conductor for the A and B lines and these three line conductors serve to provide two separate and distinct line circuits.

Since the system is of the coded duplex type it is operated through cycles during each of which transmission of controls and/or the transmission of indications may occur. When controls are transmitted the coded impulses make up code combinations for the operation of the controlling devices at the field station. Similarly when indications are transmitted the coded impulses make up code combinations for operating the indication receiving devices at the control office.

For the transmission of controls a predetermined number of impulses of selected polarities are applied to the A line circuit for operating the apparatus at the field station and the distinctive character (polarity) of these impulses determines the particular controls to be transmitted to the station.

For the transmission of indications the B line circuit is energized with impulses of distinctive character (polarity) as determined by the selective connection of one way devices (rectifiers) in the B line at the station. This selective energization of the B line is accomplished by the control office attempting to energize the B line with a (+) impulse at the beginning of an impulse period, with the station permitting the B line to be thus energized with a (+) impulse for one indication condition and preventing the B line being energized with a (+) impulse for another indication condition. When the B line is prevented from being energized with a (+) impulse then the office transfers the circuit and energizes the B line with a (—) impulse.

It will thus be seen that the B line is energized for each impulse period and this energization, irrespective of its character, causes the step-by-step operation at the office and at the station. The energization of the B line with (+) or (—) impulses at each step of a cycle provides a choice of two indications which are transmitted at each step. Since the A line is likewise energized with a (+) or a (—) impulse at each step a choice of two control conditions is transmitted at each step of the cycle.

For convenience in describing the operation of this system the energized periods of the B line circuit will be referred to as the "on" periods and the deenergized periods of the B line circuit will be referred to as the "off" periods. In the present embodiment the A and B line circuits are normally deenergized. At the start of a control cycle the B line is energized with a (—) im-

pulse for conditioning the circuits, after which the system steps through the cycle as will be explained in detail. When the system is initiated from the station the B line is energized with 5 a (+) impulse for conditioning the circuits of the system, after which the system steps through a cycle as will be explained in detail.

Other objects and advantages of the present invention will be hereinafter set forth in the 10 specification and claims and further details will be understood by referring to the accompanying drawings which illustrate the different methods of carrying out the invention by way of example.

The drawings illustrate in a diagrammatic 15 manner the apparatus and circuits employed and for convenience in describing the invention those parts which have similar features and functions are designated in the different figures by like reference characters, generally made distinctive 20 by the use of distinctive exponents representative of their location and by the use of suitable preceding numerals representative of the order of their operation and in which:

Fig. 1 illustrates in a schematic manner the 25 line circuit arrangement connecting the control office and the field station of the preferred form, showing only the apparatus most closely associated with the line circuits.

Fig. 2 illustrates in more detail the apparatus 30 and circuit arrangement (of the preferred form) employed at the control office for providing means whereby an operator may govern the switches and signals at the field station and whereby indications may be received in the control office from the field station.

Fig. 3 illustrates the apparatus and circuit arrangements somewhat in detail (of the preferred form) as employed at the field station for providing control of a single track switch and 40 for transmitting indications to the control office in accordance with the present invention.

Fig. 4 illustrates the circuits for controlling the stepping relays of Figs. 2 and 3.

When tracing the detailed circuits of the preferred form, Fig. 3 should be placed to the right 45 of Fig. 2 with correspondingly numbered lines in alignment.

For the purpose of simplifying the illustrations and facilitating in the explanation, various parts 50 and circuits have been diagrammatically shown and certain conventional illustrations have been employed. The drawings have been made more with the purpose of making it easy to understand the operation of the invention than with 55 the idea of illustrating the specific construction and arrangement that would preferably be employed in practice.

The symbols (+) and (−) are employed to 60 indicate the positive and negative terminals respectively of suitable batteries or other sources of current and the circuits with which these symbols are used have current flowing in the same direction, that is, from (+) to (−). The symbols (B+) and (B−) are employed to indicate the 65 positive and negative terminals respectively of a suitable battery or other source of current having a mid-tap (CN) and the circuits with which these symbols are used may have current flowing in one direction or the other depending upon 70 whether the terminal (B+) or (B−) is used in combination with tap (CN).

Control office equipment, preferred form.—The control office (see Fig. 2) includes a control machine having a group of control levers for controlling apparatus at the field station, a minia-

ture track layout corresponding to the track layout 5 at the station and various indicating lamps or equivalent devices, together with apparatus and circuits to accomplish the desired operation of the system.

The apparatus for a single track switch at the field station comprises a switch machine control lever SML, a self-restoring starting button SB, a miniature track switch ts and a track occupancy indicating lamp OS. It will be understood that 10 one or more additional switch machine levers may be provided if a plurality of track switches are located at the field station. It will also be understood that the single starting button SB is used irrespective of the number of control levers 15 provided.

Similarly, one or more signal control levers are provided but for convenience only a single signal control lever SGL has been illustrated, since the control of the circuits by additional levers may 20 readily be understood after an explanation of the control by the levers illustrated.

The control office includes a control line relay CF of the neutral quick acting type. A stepping line relay 1SF of the biased-to-neutral polar 25 type is provided for controlling the stepping operation and for receiving the indications at the control office. A second stepping line relay 2SF is provided for controlling the operation of an extra impulse relay PX, the purpose of which 30 will be described in detail. Relay 1SF controls a line repeating relay FP which repeats the energization of relay 1SF irrespective of the polarity of energization of the B line circuit. A slow acting line repeating relay SA is controlled by relay 35 FP to mark the bounds of a cycle of operations, that is, relay SA is picked up at the beginning of a cycle, remains picked up during the impulses of a cycle and is dropped at the end of the cycle after a predetermined period of time has been 40 measured off following the last impulse.

Associated with the line repeating relays is a bank of stepping relays including relays VP, 1V and 2V. This bank of relays is for the purpose of marking off the successive steps of each cycle, 45 since the particular circuit arrangement for the stepping relays is immaterial for an understanding of the present invention, this circuit arrangement is not shown in Figs. 2 and 3 but only indicated by the dotted line connecting front contact 50 28 of relay SA with the relays VP, 1V and 2V. The control circuits for these relays VP, 1V and 2V have been shown in Fig. 4, but for the detailed operation of the stepping relay bank reference is made to Fig. 2 of the parent Patent No. 55 2,169,480 granted August 15, 1939. Referring to Fig. 4 the impulses of each cycle cause intermittent energization of the line repeater relay FP. The initial picking up of this relay FP causes the slow acting relay SA to be picked up as is evident from the control circuits of relays SA shown in Figs. 2 and 3. With the relay SA now in its attracted condition and with the relay FP energized a pick-up circuit is closed for the half-step relay VP which starts from the (+) terminal of 60 a battery and includes the front contact 130 of the relay SA, the front contact 131 of the relay FP, back contact 132 of the stepping relay 2V, back contact 133 of the stepping relay 1V, through the winding of the relay VP to the other 65 terminal (−) of a battery. As soon as the relay VP assumes its energized position a stick circuit for this relay including the front contact 130 of relay SA and the stick contact 134 of the relay VP is closed. With the relay VP now energized and 70 75

the relay FP deenergized during the next "off" period of the B line a pick-up circuit for the first stepping relay IV is closed which may be traced as follows: beginning at the terminal (+), 5 front contact 135 of the relay SA, back contact 136 of the relay FP, front contact 137 of the relay VP, back contact 138 of the relay 2V, through the winding of the relay IV to the terminal (-). With the first stepping relay IV picked up it will 10 be stuck up through a stick circuit including front contact 140 of relay SA and stick contact 141 of relay IV. Also, with the relay FP now deenergized a second stick circuit for the relay VP is closed which includes the front contact 130 of 15 the relay SA, the back contact 131 of the relay FP and the stick contact 142 of the relay VP. The first traced stick circuit for the relay VP is, of course, broken when the first stepping relay IV is picked up. Picking up of the relay FP during 20 the second impulse of the cycle causes the second traced stick circuit for the relay VP to be broken thereby causing deenergization of the relay VP there being no available pick-up circuit for this relay VP with the relay IV energized and 25 the relay 2V deenergized. During the second deenergization of the B line and deenergization of the relay FP a pick-up circuit for the relay 2V is closed which may be traced through the front contact 135 of relay SA, the back contact 136 of 30 relay FP, back contact 137 of relay VP, the front contact 143 of relay IV, to the winding of the relay 2V. With this relay 2V once energized it is stuck up through a stick circuit including the front contact 140 of relay SA and the stick contact 145 of stepping relay 2V. In the same manner as just described for stepping relays IV and 35 2V any number of stepping relays may be successively picked up one during each deenergization of the intermittently closed B line of the 40 system. At the end of an operating cycle the slow dropping relay SA will of course assume its deenergized position thereby breaking all of the pick-up and stick circuits for the stepping relays V and also breaking all of the control circuits for 45 the relay VP.

An impulse controlling relay E is controlled by the stepping relays, this impulse controlling relay operating to connect and disconnect current to the A and B line circuits during the "on" and 50 "off" periods. The A line circuit is energized with a (+) impulse from line battery LB when positive polarity controlling relay PC is picked up and with a (-) impulse when negative polarity controlling relay NC is picked up. This polarity of energization is determined during the "off" periods while impulse relay E is energized, after which the A line is energized with a selected polarity when relay E drops to mark the end of the "off" periods. 55

Indication receiving relays 1IR and 2IR are provided to receive the indication which is transmitted from the field station at the particular steps of the cycle as selected by the operation of the stepping relay bank in the control office. These relays are of the polar magnetic stick type, that is, their contacts remain in the positions to which they were last actuated until shifted by the energization of their windings with an impulse of opposite polarity. Relay 1IR receives the indication as to whether or not the track section at the field station is occupied and indicates this condition by energizing or deenergizing lamp OS. Relay 2IR may receive any other indication required, but since the operation of relay 1IR is typical of the operation of other indi- 60

cation receiving relays the control of indicating devices by relay 2IR is not shown.

Field station equipment, preferred form.—The field station (see Fig. 3) comprises a turnout track connected to a main track by means of a track switch TS. This track switch is operated from one extreme locked position to the other by a suitable switch machine SM. The switch machine is controlled by a switch machine control relay SMR of the two-position polar magnetic stick type which is governed from the control office through the medium of the communication system herein disclosed. Relay SMR controls the operation of the switch machine by energizing its normal or reverse operating wires from a local source of current as controlled by contact 100. This control preferably includes suitable approach locking and other automatic signalling means as usually employed but not shown in the present disclosure for the sake of 15 simplicity.

Suitable signals are associated with track switch TS for governing traffic thereover. These signals are also governed from the control office through the medium of the communication system in any suitable way by means of control relays, such as relay SGR, operated from the control office in a similar manner as the switch machine control relay SMR. The detailed circuit arrangement of the signal control at the field 20 station has been omitted from the present disclosure since it is immaterial for an understanding of the present invention.

The detector track section has a normally closed track circuit with the usual track battery 35 and track relay T for indicating the passage of trains.

The communication part of the system includes control line relay CF¹ and stepping line relay SF¹, the latter being a quick acting neutral type relay, while relay CF¹ is a biased-to-neutral polar relay of the quick acting type. Relays FP¹ and SA¹ are the line repeating relays at the station, similar to corresponding relays in the control office.

The field station includes a bank of stepping relays VP¹, IV² and 2V¹ operating in synchronism with the control office stepping relay bank and since the detailed circuit arrangement for operating these relays is immaterial for an understanding of the present invention their control has merely been indicated by the dotted line extending from front contact 120 of relay SA¹ to the stepping relays.

A change relay CH¹ is provided to register a 55 change in condition of any of the traffic controlling devices at the station so that the system will be initiated for the transmission of new indications. The detailed control of this relay has not been shown since it is well known in the art how such a relay is made responsive to a change in condition of traffic controlling devices and re-sensitized during the succeeding cycle of operations so that it may respond to the next change. This change relay CH¹ may be controlled in the same 60 manner as the change relay of Patent No. 2,082,544 to Judge is controlled. The front contact of the lock relay will of course be omitted from the pick-up circuit in a system where no lock-out relay is employed, as is true of the system of the instant application. Impulse relay PL is provided for selectively connecting rectifiers 1RF and 2RF to the B line conductor as determined by the condition of the traffic controlling devices, which are to transmit these conditions 70 75

to the control office by means of indications. It will be understood that these rectifiers may be of any approved type for permitting current to flow through each one in only one direction, such as the well known copper-oxide rectifier.

For the purpose of indicating how the two different indication conditions are transmitted by the energization or the deenergization of relay PL, relay M is shown with its back contact 101 closed and relay T is shown with its back contact 113 open. Relay M may be the usual relay which repeats the condition of the signals associated with the illustrated track section, this relay being energized when all of the signals are at stop and deenergized when some one of the signals is in its proceed condition.

It is believed that the nature of the invention, its advantages and characteristic features will best be understood with further description being set forth from the standpoint of operation.

Operation

The system of the present invention is normally in a condition of rest, from which it may be initiated into a cycle of operations either from the control office or from the field station when there are new controls or new indications ready to transmit.

Irrespective of whether a cycle is to be for the transmission of controls or the transmission of indications, a predetermined number of impulses are placed upon stepping line B to accomplish the step-by-step operation of the stepping relay banks. These impulses are time spaced, that is, they follow each other at definite time intervals.

When a cycle is initiated for the transmission of controls the character of the impulses placed upon the A line circuit is determined in accordance with the positions of the control levers in the control office. During such a cycle indications are transmitted by means of the character of the impulses placed upon the B line circuit, as determined by the positions of the control devices at the field station as repeated by relays T and M for example.

When a cycle of operations is initiated from the control office a series of indications are transmitted from the station to the office during this cycle irrespective of whether a change in condition of the control devices has taken place or not. Likewise, when a cycle of operations is initiated from a field station the conditions of the control levers in the office at that time are transmitted to the field station irrespective of whether the starting button in the control office has been actuated or not. It will thus be seen that the present invention provides for duplex operation of the system, that is, controls and indications are transmitted during a single cycle of operations.

Normal conditions.—Although the system may be initiated from the field station, both line circuits are normally deenergized. In order to provide a means for initiating the system from the field station the normally deenergized B line circuit is energized in response to the dropping of change relay CH¹. Change relay CH¹ is in its normally energized condition as previously mentioned and track relay T is normally energized when the associated track section is unoccupied. The remaining circuits of the system both at the field station and at the control office are normally deenergized.

Manual start.—With the system in a condition of rest it may be manually initiated into a cycle

for the transmission of controls. Whenever such a cycle is desired the operator first positions the control levers and then actuates the starting button.

For the purpose of considering the operation of the present system it will be assumed that lever SML is in its right hand normal position and that lever SGL is in its center stop position. The actuation of starting button SB closes a circuit for picking up relay PX which extends from (+), back contact 23 of relay E, back contact 22 of relay IV, contact 11 of button SB and winding of relay PX, to (-).

The picking up of relay PX closes a circuit for energizing the B line circuit with a (-) potential and the C line conductor with a (+) potential. This circuit extends from (+) at the midtap C of battery LB in the control office, back contact 12 of relay E, C line conductor 13, rectifier 2RF, back contact 102 of relay PL, winding of relay SF¹, B line conductor 14, windings of relays 1SF and 2SF in series and front contact 15 of relay PX to the (-) terminal of battery LB. The A line circuit is deenergized at this time since both relays PC and NC are deenergized.

Relays 1SF, 2SF and SF¹ are picked up by means of current flowing over this circuit, with relay 1SF positioning its polar contacts to the left. A circuit is now closed for picking up relay FP which extends from (+), contact 16 of relay 1SF in its left hand dotted position and winding of relay FP to (-). Relay SA is energized over a circuit extending from (+), front contact 17 of relay FP and winding of relay SA to (-).

The energization of relays FP and SA effect the picking up of relay VP over a circuit including front contact 130 of the relay SA, front contact 131 of relay FP, and contacts of the stepping relays (see Fig. 4). The operation of relays VP, IV and 2V will be pointed out at the times when these relays shift their positions. The stepping relays are energized during the "off" periods and the VP relay is shifted during the "on" periods, which is the operation desired and assumed in the present embodiment. It should be understood that relays corresponding to the relays shown in Fig. 4 are employed at the field station and these relays operate in synchronism with those in the control office.

The picking up of relay VP closes a circuit for picking up relay E which extends from (+), back contact 18 of relay 2V, back contact 19 of relay IV, front contact 21 of relay VP and winding of relay E to (-). It will thus be seen that the picking up of relay PX marks the beginning of what may be conveniently termed the conditioning "on" period by energizing the B line circuit. The operation of relays SF¹, 1SF, 2SF, FP, SA, VP and E takes place during this conditioning period.

The picking up of relay E marks the end of the conditioning "on" period and the beginning of the first "off" period by deenergizing the above traced B line circuit at back contact 12. The picking up of relay E opens the circuit of relay PX at contact 23 which allows this relay to drop.

The deenergization of the B line circuit effects the dropping of relays 1SF, 2SF and SF¹. Relay FP is deenergized by the shifting of contact 16 of relay 1SF to its neutral position. This effects the picking up of relay IV which in turn drops relay E by opening the above described circuit at back contact 19. The picking up of relay IV closes the selecting circuit of the PC and NC relays and since lever SML is in its right hand

position this circuit includes relay PC and extends from (+), back contact 24 of relay 2V, front contact 25 of relay 1V, contact of lever SML in its right hand position, PC bus and winding of relay PC, to (-). It will be obvious that relay NC would be energized with the contact of lever SML in its left hand dotted (reverse) position.

The A line conductor 33 is now energized with (+) potential over a circuit extending from the (+) terminal of battery LB, front contact 26 of relay PC, back contact 36 of relay NC, winding of relay CF, A line conductor 33, winding of relay CF¹, C line conductor 13 and back contact 12 of relay E to the mid-tap of battery LB. Current flowing over this circuit energizes relays CF and CF¹, the latter positioning its polar contacts to the right. A circuit is now closed for picking up relay PX which extends from (+), front contact 27 of relay CF, back contact 28 of relay 2SF and winding of relay PX to (-). Relay PX closes a stick circuit for itself extending from (+), front contact 27 of relay CF, back contact 29 of relay E, front contact 39 and winding of relay PX to (-).

The energization of relay PX applies (-) potential to the B line circuit at its front contact 15, as previously described, and since the (+) terminal of battery LB is connected to the A line at front contact 26 of relay PC, current flows over these two lines in series with the C line conductor 13 occupying the neutral branch of the circuit so that this latter conductor may or may not be deenergized, as determined by the resistance values of the A and B line circuits. The energization of the B line circuit from the (-) terminal of battery LB effects the picking up of relay 2SF and the positioning of the contacts of relay 1SF to the left. Relay SF¹ at the station is picked up. The closure of contact 16 of relay 1SF in its left hand dotted position again picks up relay FP, which effects the deenergization of relay VP.

A circuit is now closed for picking up relay E which extends from (+), back contact 18 of relay 2V, front contact 19 of relay 1V, back contact 21 of relay VP and winding of relay E, to (-). The energization of relay E opens the stick circuit of relay PX at back contact 29 and since relay 2SF is energized its back contact 28 is open, resulting in the dropping of relay PX to mark the end of the first "on" period and the beginning of the second "off" period by deenergizing the A and B line circuits by opening front contact 15. It will be observed that the (+) terminal of battery LB is connected to the B line conductor through back contact 15 of relay PX and to the A line conductor through front contact 26 of relay PC, with the C line conductor open at back contact 12 so that there is no circuit for energizing either line circuit at this time.

Relays 1SF, 2SF and SF¹ are deenergized and with contact 16 of relay 1SF assuming its neutral position relay FP is deenergized. Relay 2V is now picked up and the selecting circuit for the PC and NC relays is transferred to front contact 24 of relay 2V. Since it is assumed that lever SGL is in its mid position a circuit is closed for immediately reenergizing relay PC which extends from (+), front contact 24 of relay 2V, lever SGL in its mid position, PC bus and winding of relay PC to (-). The picking up of relay

2V deenergizes the above described circuit of relay E at back contact 18.

The dropping of relay E marks the end of the second "off" period and the beginning of the second "on" period by energizing the A line circuit with a (+) impulse and the B line circuit with a (+) impulse. This change in energization of the B line circuit is due to the fact that relay PL at the station is energized as will be described in connection with the transmission of indications. For the present it will be assumed that relay PL is picked up so that a circuit for energizing the B line with a (+) impulse may be traced from the (+) terminal of battery LB, back contact 15 of relay PX, windings of relays 2SF and 1SF in series, B line conductor 14, winding of relay SF¹, front contact 102 of relay PL, rectifier 1RF, C line conductor 13 and back contact 12 of relay E to the midtap of battery LB. The A line is energized during this "on" period with a (+) potential over a circuit extending from the (+) terminal of battery LB, front contact 26 of relay PC, back contact 36 of relay NC, winding of relay CF, A line conductor 33, winding of relay CF¹, C line conductor 13 and back contact 12 of relay E to the midtap of battery LB.

Relays 1SF, 2SF and SF¹ are energized over the B line circuit above traced, with relay 1SF positioning its polar contacts to the right. Relays CF and CF¹ are energized over the A line circuit above traced, with relay CF¹ positioning its polar contact to the right. Relay 1SF effects the energization of relay FP as before, after which relay VP is picked up to energize relay E over a circuit extending from (+), front contact 18 of relay 2V, front contact 21 of relay VP and winding of relay E to (-).

The picking up of relay E marks the end of the second "on" period and the beginning of the change to normal "off" period, which is of comparatively long duration because there are no more steps to be taken. The A and B line circuits are deenergized by the picking up of back contact 12 of relay E, it being recalled that the (+) terminal of battery LB is connected to both A and B line conductors.

The deenergization of the B line circuit effects the dropping of relays 1SF, 2SF and SF¹. The shifting of contact 16 of relay 1SF to its neutral position deenergizes relay FP and, since there is no circuit effective at this time to deenergize relay E, relay FP remains deenergized for a sufficiently long period of time to effect the dropping of slow acting relay SA. Relay SA in releasing by the opening of its contacts 130 and 148 deenergizes relays VP, 1V and 2V by deenergizing their stick circuits (see Fig. 4). The restoration of the stepping relay bank to normal deenergizes relay E and the selected polarity control relay (in this instance relay PC). The deenergization of the A line circuit causes relays CF and CF¹ to restore to normal.

During the above description it has been pointed out that relay SF¹ at the field station operates in synchronism with relay 1SF in the control office. Therefore the intermittent closure of front contact 103 of relay SF¹ operates relay FP¹ in synchronism with relay FP in the control office. Furthermore the intermittent closure of front contact 104 of relay FP¹ energizes relay SA¹ during the conditioning "on" period above described and maintains this relay in its picked up position during the following impulses of the cycle. Since relay FP¹ opens its front contact 104 for a comparatively long internal of time at the end of the

cycle, relay SA¹ is released at approximately the same time as relay SA in the control office.

It will also be mentioned at this time that relays VP¹, 1V¹ and 2V¹ are operated in synchronism with corresponding relays in the control office by means of circuits shown in Fig. 4 of the drawings. These stepping relays are deenergized at the end of the cycle the same as those in the control office.

Polarity selection of control impulses.—When 10 the system is initiated from the control office as above described, the first (conditioning) impulse applied to the B line circuit is (—) in character by reason of the picking up of relay PX. This application of energy to the B line causes various 15 relay operations which have already been described.

Assuming that the switch machine lever is in its right hand (normal) position as shown, the first "on" impulse applied to the A line circuit is 20 (+) as already described. In the event that lever SML is in its left hand dotted (reverse) position relay NC is energized to apply a (—) impulse to the A line circuit.

This selection of the polarity of energization for 25 the A line circuit occurs on each step by reason of the selection made at contacts 25 of relay 1V, 24 of relay 2V, etc. This selectively energizes relay PC or NC in accordance with the particular position of the control lever selected 30 for each step. It will be understood that additional levers for other control purposes may be provided and selected through additional contacts of additional stepping relays when the size of the system requires such extra selection.

35 From the above it will be seen that the impulse applied to the B line during the conditioning period of a cycle initiated in the control office is (—), with the following impulses applied to the A line circuit being (+) or (—) in character 40 dependent upon the positions of the control levers rendered effective by the stepping relays at the various steps of the cycle. This polarity determination is accomplished by two polarity determining relays PC and NC which are selectively 45 energized during the "off" or deenergized periods of the line circuits in readiness for energizing the control line circuit during succeeding "on" or energized periods with the proper polarities as selected.

50 *Transmission of controls.*—Upon the transmission of the first impulse, following the conditioning impulse, relay SMR at the field station is energized for actuating its polar contact 100 to the right or to the left depending upon the character 55 of the impulse received. With lever SML in its normal position as shown, the (+) impulse applied to the A line circuit actuated the contacts of relay CF¹ to the right. A circuit is now closed for actuating the contacts of relay SMR to the right extending from (B+), contact 105 of relay CF¹ in its right hand dotted position, back contact 106 of relay 2V¹, front contact 107 of relay 1V¹ and winding of relay SMR to (CN). This energization of relay SMR closes contact 108 in its 60 right hand position for applying energy to the normal operating winding of switch machine SM for operating the track switch to its normal locked position.

In the event that lever SML is in its left hand 70 (reverse) position the (—) impulse applied to the A line circuit actuates contact 105 of relay CF¹ to the left, which applies (B—) to the circuit above described including relay SMR. This positions contact 108 to the left for applying energy to the reverse operating winding of switch machine SM

which operates the track switch to its reverse locked position.

In a similar manner lever SGL in its neutral position causes relay PC to be picked up for applying a (+) impulse to the A line circuit when the 5 second step is taken, which actuates contact 105 of relay CF to the right for applying (B+) to the winding of relay SGR over a circuit including front contact 106 of relay 2V¹. It is believed unnecessary to show or explain the detailed operation of the circuits controlled by relay SGR since they form no part of the present invention.

Field start.—This system is of the coded duplex type and indications are transmitted from the station to the control office during the same cycle 15 that controls are transmitted to the station.

Referring to Fig. 3, a change in the condition of the detector track section or a change in the condition of other traffic devices at the station may occur at any time and for convenience in describing the operation of this portion of the system it will be assumed that such change effects the deenergization of relay CH¹. The dropping of relay CH¹ closes a circuit for picking up relay PL which extends from (+), back contact 103 of 25 relay SF¹, back contact 112 of relay CH¹, back contact 113 of relay 1V¹, back contact 119 of relay 2V¹ and winding of relay PL to (—). Relay PL closes a stick circuit for itself extending from (+), front contact 110 of relay PL, back contact 30 111 of relay 1V¹, back contact 112 of relay CH¹ and over the previously described circuit to the winding of relay PL.

The energization of relay PL causes the B line to be energized with (+) potential over a circuit 35 extending from the (+) terminal of battery LB, back contact 15 of relay PX, windings of relays 2SF and 1SF in series, B line conductor 14, winding of relay SF¹, front contact 102 of relay PL, rectifier 1RF, C line conductor 13 and back contact 40 12 of relay E to the midtap of battery LB.

This energization of the B line circuit picks up 45 relays 2SF, 1SF and SF¹. In response to the actuation of contact 16 of relay 1SF (to the right in this instance since the B line circuit is energized (+)), relays FP and SA are energized to initiate the cycle. Relays VP and E are energized as previously described in connection with a control cycle to complete the conditioning "on" 50 period. The energization of relay E marks the beginning of the first "off" period and the system steps through its cycle as before.

During the first "off" period relay 1V¹ is picked up to deenergize, at its back contact 111, the above described stick circuit for relay PL so that this relay is now made dependent for its energization upon the circuits selected by the stepping relays and controlled by traffic devices such as track relay T and signal repeating relay M.

60 *Transmission of indications.*—After thus having initiated the system from the field station the controls are transmitted as previously described to actuate the control relays in accordance with the positions of the control levers in the office. During the steps of the cycle indications are transmitted by relay PL selectively governing the energization of the B line circuit by means of rectifiers 1RF and 2RF. For example, with the track relay energized when 70 the first step is taken, the circuit leading to (+) at back contact 113 of relay T is opened so that relay PL will not be picked up. During this "off" period the dropping of relay E energizes the A line circuit as previously described and since re- 75

lay PX is deenergized, (+) potential is applied through its back contact 15 to the B line circuit, but since back contact 102 of relay PL is closed no current can flow through rectifier 2RF over this circuit.

The picking up of relay CF in response to the energization of the A line picks up relay PX to mark the end of the first "off" period and the beginning of the first "on" period as previously described. The picking up of relay PX applies a (−) impulse to the B line circuit for positioning the contacts of relay 1SF to the left which closes a circuit for actuating relay 1IR to the left extending from (B−), contact 30 of relay 1SF in its left hand dotted position, back contact 31 of relay 2V, front contact 32 of relay 1V and winding of relay 1IR to (CN). With contact 34 of relay 1IR in its left hand position, lamp OS is deenergized. In the event that track relay T is deenergized under the above condition, then relay PL is energized and relay 1SF is actuated to the right for positioning relay 1IR to the right to close a circuit through contact 34, which energizes lamp OS to give the indication that the track section is occupied. The manner in which relay 1SF is positioned to the right will now be explained in connection with the second step of the cycle.

Assuming that relay M is deenergized, relay 30 PL is energized, when the second step is taken, over a circuit extending from (+), back contact 101 of relay M, front contact 119 of relay 2V¹ and winding of relay PL to (−).

When relay E is deenergized to mark the beginning of the next "on" period both the A and B line circuits are energized with (+) potential. The A line circuit is energized with (+) potential because relay PC is picked up. The B line circuit cannot be energized with (−) potential as before because contact 102 of relay PL disconnects rectifier 2RF from the B line circuit and inserts rectifier 1RF which will only permit energization of the B line circuit with a (+) impulse. Therefore the A and B line circuits are simultaneously energized under this condition instead of the A line circuit being energized in advance of the B line circuit as before. This prevents the picking up of relay PX because contact 28 of relay 2SF is opened by the time front contact 27 of relay CF is closed. With relay PX deenergized the B line circuit continues to be energized from the (+) terminal of battery LB throughout this "on" period. This positions contact 30 of relay 1SF to the right for closing a circuit which actuates relay 2IR to the right and which extends from (B+), contact 30 of relay 1SF in its right hand dotted position, front contact 31 of relay 2V and winding of relay 2IR to (CN).

Although the transmission of indications has only been shown for two steps it will be understood that any number of steps may be similarly employed, each step providing for the transmission of a choice of two indications.

During a cycle of operations for the transmission of indications as just described, change relay CH¹ at the station is restored to its picked up position in readiness for any other change that may occur at the field station. The circuit arrangement for accomplishing this result is not shown since it is immaterial for an understanding of the present invention and since various expedients may be used for such accomplishment.

The change to normal period at the end of the

cycle effects the deenergization of the various relays in the same manner described in connection with a control cycle.

Duplex operation.—It has been pointed out that control and indication cycles are initiated from the control office and the field station respectively. It has also been mentioned that indications of the existing conditions of the control devices at the station are transmitted to the office during a control cycle and controls are transmitted from the office to the field station in accordance with the existing conditions of the control levers during an indication cycle. Thus the resulting cycle of operations initiated from the control office or from the field station results in two way transmission, or in other words the duplex operation of the system.

Having thus described a centralized traffic controlling system as a preferred form, it is desired to be understood that the particular form illustrated was selected to facilitate in the disclosure rather than to limit the form the invention may assume or its scope and it is further to be understood that various modifications, adaptations, and alterations may be applied to the specific form shown to meet the requirements of practice without departing from the spirit of the invention except as limited by the appended claims.

What I claim is:

1. In a remote control system, a control office and a field station connected by a line circuit; impulsive means at said office for applying a series of current impulses to said line circuit, means in said office for attempting to mark each of said impulses with one polarity, a first rectifier at said station for preventing said office from marking an impulse with said one polarity, means in said office responsive to its failure to mark an impulse with said one polarity for marking said impulse with another polarity, a second rectifier at said station for permitting said office to mark said impulse with said one polarity, and means responsive to the polarity with which said impulse is marked for transmitting a code message from said station to said office.

2. In a remote control system; a control office and a field station connected by a line circuit; means including a source of energy for energizing said line circuit with current of one polarity; impulsive means in said office for intermittently opening and closing said line circuit, whereby a series of time spaced impulses are applied thereto; step-by-step mechanisms in said office and at said station operated in synchronism in response to said impulses; means at said station for preventing the energization of said line circuit with current of said one polarity at certain steps of said mechanisms; means in said office responsive to the failure to energize said line circuit with current of said one polarity for applying current of another polarity thereto, whereby said line circuit is energized with current of another polarity; and means in said office distinctively responsive to the polarity with which said line circuit is energized, whereby coded messages are transmitted from said station to said office.

3. In a remote control system; a control office and a field station connected by a line circuit; means including a source of energy for energizing said line circuit with current of one polarity; impulsive means in said office for intermittently opening and closing said line circuit, whereby a series of time spaced impulses are ap-

- plied thereto; step-by-step mechanisms in said office and at said station operated in synchronism in response to said impulses; means at said station for permitting or preventing the energization of said line circuit with current of said one polarity at certain steps of said mechanisms; means in said office responsive to the failure to energize said line circuit with current of said one polarity for applying current of another polarity thereto, whereby said line circuit is energized with current of another polarity; means in said office responsive to the energization of said line circuit with current of said one polarity for preventing the application of current of said other polarity thereto; and means in said office distinctively responsive to the polarity with which said line circuit is energized, whereby coded messages are transmitted from said station to said office.
20. 4. In a remote control system, a control office, a field station, a line circuit connecting said office with said station, means in said office for applying a series of direct current impulses of particular polarity to said line circuit, means at said office for time spacing said impulses, a rectifier device at said station for at times blocking the flow of a current impulse in said line circuit, means at said office for reversing the polarity of such particular impulse when the polarity of such impulse as originally applied is in disagreement with said rectifier, and indicating means at said control office controlled by the current impulses actually flowing in said line circuit and in accordance with their polarity.
25. 5. In a remote control system, a control office, a field station, step-by-step mechanisms at said office and at said station, a line circuit connecting said office with said station, means at said office for applying a series of impulses of direct current to said line circuit, means responsive to said series of impulses for operating said mechanisms in synchronism, means including a rectifier device in said line circuit at said station and electro-responsive means in said line circuit at said office to characterize the polarities of said impulses to conform with the rectifying direction of said rectifier, and means responsive to the character of said impulses for transmitting messages from said station to said office during the synchronous operation of said mechanisms.
30. 6. In a remote control system; a control office; a field station; a source of energy at said office; a line circuit connecting said office and said station; a line relay in said circuit at said office; control means for supplying current of one polarity from said source to said line circuit; electric valve means included in said line circuit at said field station in a direction in accordance with the message to be transmitted to said office; electro-responsive means controlled by said control means and by said relay for reversing the polarity of current applied at said office to said line circuit when said control means is operated to apply current to said line circuit and said line relay does not respond thereto by reason of the blocking action of said electric valve means, to thereby cause said relay to respond to such reversing of the current; and indicating means controlled by said line relay.
35. 7. In a remote control system, a stepping line circuit having a plurality of series of time-spaced impulses impressed thereon, a step-by-step mechanism operable through a separate cycle for each of said series of impulses, means controlled by said mechanism for selecting a channel cir-
- cuit for each step, means for causing said mechanism to take one step for each impulse of a series, two oppositely poled rectifiers at the sending station of said system, means for selectively connecting said rectifiers only one at one time 5 in said line circuit on each step of said step-by-step mechanism to characterize a code, means at the receiving station for applying current of one polarity to said line circuit on a particular step and if the rectifier then connected in said line circuit does not allow said current of that polarity to flow to cause the application of current of a different polarity to said line circuit, and indicating devices included in said channel circuits controlled in accordance with the polarity 10 of the current flowing in said line circuit on corresponding steps.
8. In a remote control system, a stepping line circuit connecting an office and a field station, means at said office for applying a plurality of series of time-spaced stepping impulses upon said line circuit, a step-by-step mechanism at said office and at said field station operable through a separate cycle for each of said series of stepping impulses, means for causing said mechanisms to take one step for each stepping impulse of a series, a second line circuit, means for impressing a series of current impulses on said second line circuit one impulse for each step in synchronism with the application of said stepping impulses on said stepping line, means controlled by said mechanisms for selecting a plurality of channel circuits at least one for each step, two oppositely poled one way current devices, means for selectively connecting one or the other of said devices in said stepping line circuit on each step, means controlled by impulses in said second line circuit for reversing the polarity of current in said first line circuit in the event a current impulse flows in said second line circuit before a current impulse flows in said first line circuit due to the one way current device included in said first line circuit blocking the flow of current in said first line circuit, and indicating devices controlled over said channel 30 circuits in accordance with the polarity of current flowing in said stepping line circuit.
9. In a remote control system, a first line circuit connecting an office and a field station, a second line circuit connecting said office and said field station, a line relay in said first line circuit at said office and at said field station, step-by-step mechanism at said office and at said field stations controlled by said line relays, a source of current in said line circuit at said office, means in said office for intermittently closing said line circuits to establish a series of current impulses, rectifier means at said field station included in said first line circuit and normally so poled as to prevent the flow of current in said first line circuit due to closure of said line circuits at said office, means including a line relay in said second line circuit at said office for pole changing the source of current in said first line circuit if said second line circuit is energized before said first line circuit is energized to cause current to flow through said rectifier means in said first line circuit, means at said field station controlled by the step-by-step mechanism at said field station for including said rectifier means in one rectifying direction or the other in said first line circuit on each step depending on traffic conditions at said station, indicating means at said office, and polar contacts on said line relay in said first line circuit at said office for controlling 40
45. 10. In a remote control system, a first line circuit connecting an office and a field station, a second line circuit connecting said office and said field station, a line relay in said first line circuit at said office and at said field station, step-by-step mechanism at said office and at said field stations controlled by said line relays, a source of current in said line circuit at said office, means in said office for intermittently closing said line circuits to establish a series of current impulses, rectifier means at said field station included in said first line circuit and normally so poled as to prevent the flow of current in said first line circuit due to closure of said line circuits at said office, means including a line relay in said second line circuit at said office for pole changing the source of current in said first line circuit if said second line circuit is energized before said first line circuit is energized to cause current to flow through said rectifier means in said first line circuit, means at said field station controlled by the step-by-step mechanism at said field station for including said rectifier means in one rectifying direction or the other in said first line circuit on each step depending on traffic conditions at said station, indicating means at said office, and polar contacts on said line relay in said first line circuit at said office for controlling 50
55. 11. In a remote control system, a first line circuit connecting an office and a field station, a second line circuit connecting said office and said field station, a line relay in said first line circuit at said office and at said field station, step-by-step mechanism at said office and at said field stations controlled by said line relays, a source of current in said line circuit at said office, means in said office for intermittently closing said line circuits to establish a series of current impulses, rectifier means at said field station included in said first line circuit and normally so poled as to prevent the flow of current in said first line circuit due to closure of said line circuits at said office, means including a line relay in said second line circuit at said office for pole changing the source of current in said first line circuit if said second line circuit is energized before said first line circuit is energized to cause current to flow through said rectifier means in said first line circuit, means at said field station controlled by the step-by-step mechanism at said field station for including said rectifier means in one rectifying direction or the other in said first line circuit on each step depending on traffic conditions at said station, indicating means at said office, and polar contacts on said line relay in said first line circuit at said office for controlling 60
65. 12. In a remote control system, a first line circuit connecting an office and a field station, a second line circuit connecting said office and said field station, a line relay in said first line circuit at said office and at said field station, step-by-step mechanism at said office and at said field stations controlled by said line relays, a source of current in said line circuit at said office, means in said office for intermittently closing said line circuits to establish a series of current impulses, rectifier means at said field station included in said first line circuit and normally so poled as to prevent the flow of current in said first line circuit due to closure of said line circuits at said office, means including a line relay in said second line circuit at said office for pole changing the source of current in said first line circuit if said second line circuit is energized before said first line circuit is energized to cause current to flow through said rectifier means in said first line circuit, means at said field station controlled by the step-by-step mechanism at said field station for including said rectifier means in one rectifying direction or the other in said first line circuit on each step depending on traffic conditions at said station, indicating means at said office, and polar contacts on said line relay in said first line circuit at said office for controlling 70
75. 13. In a remote control system, a first line circuit connecting an office and a field station, a second line circuit connecting said office and said field station, a line relay in said first line circuit at said office and at said field station, step-by-step mechanism at said office and at said field stations controlled by said line relays, a source of current in said line circuit at said office, means in said office for intermittently closing said line circuits to establish a series of current impulses, rectifier means at said field station included in said first line circuit and normally so poled as to prevent the flow of current in said first line circuit due to closure of said line circuits at said office, means including a line relay in said second line circuit at said office for pole changing the source of current in said first line circuit if said second line circuit is energized before said first line circuit is energized to cause current to flow through said rectifier means in said first line circuit, means at said field station controlled by the step-by-step mechanism at said field station for including said rectifier means in one rectifying direction or the other in said first line circuit on each step depending on traffic conditions at said station, indicating means at said office, and polar contacts on said line relay in said first line circuit at said office for controlling 75

said indicators in accordance with the rectifying direction said rectifying means is included in said first line circuit on each step.

10. In a remote control system, a control office and a field station, a control circuit and a stepping circuit connecting said office and field station, line relays in said stepping circuit at said office and at said field station, step-by-step mechanism at said office and at said field station controlled by said line relays, a distinctive current responsive line relay at said field station and a neutral relay at said office included in said control circuit, means including said step-by-step
- mechanism at said office for applying current impulses of distinctive characters to said control circuit one impulse for each step to characterize a code, means controlled by said neutral relay and including a front contact thereof for applying stepping impulses to said stepping line circuit one impulse for each energization of said neutral relay, and controlled means at said field station controlled by said distinctive impulses through the medium of said distinctive current responsive relay at said field station. 5 10

NEIL D. PRESTON,
